United States Patent Office

Des. 188,924
Patented Sept. 27, 1960

188,924

CARBURETOR

George L. Holzapfel, Newbury Park, Calif., assignor of
eighty percent to Concha Holzapfel, Newbury Park,
and twenty percent to Thomas P. Mahoney, Pacific
Palisades, Calif.

Filed Feb. 9, 1959, Ser. No. 54,532

Term of patent 14 years

(Cl. D77—1)

Fig. 5

Fig. 1 is a side elevational view of a carburetor showing my new design;

Fig. 2 is an end elevational view thereof;

Fig. 3 is a bottom plan view thereof;

Fig. 4 is an elevational view thereof as seen from the opposite side of Fig. 1; and

Fig. 5 is an enlarged perspective view thereof as seen from the top right of Fig. 1.

I claim:

The ornamental design for a carburetor, as shown.
